Primary Examiner — Robert M Spear*Assistant Examiner* — Eliza Bennett-Hattan(74) *Attorney, Agent, or Firm* — Krieg DeVault LLP(57) **CLAIM**

The ornamental design for an arm of spectacles, as shown and described.

DESCRIPTION

The sole FIGURE is a side view of the arm of spectacles of the present invention.

The broken lines in the drawing depict environmental subject matter only and form no part of the claimed design. The claimed design is flat and planar.
